[57] **CLAIM**

The ornamental design for a shoe upper, as shown and described.

DESCRIPTION

FIG. 1 is a left side elevational view of a shoe upper showing our new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view of a shoe upper showing an alternate embodiment of our new design;

FIG. 7 is a right side elevational view thereof;

FIG. 8 is a top plan view thereof;

FIG. 9 is a front elevational view thereof;

FIG. 10 is a rear elevational view thereof;

FIG. 11 is a left side elevational view of a shoe upper showing another alternate embodiment of our new design;

FIG. 12 is a right side elevational view thereof;

FIG. 13 is a top plan view thereof;

FIG. 14 is a front elevational view thereof; and

FIG. 15 is a rear elevational view thereof.

The broken line showing of a shoe sole in the figures is environmental only and forms no part of the claimed design.

FIG. 1**FIG. 2****FIG. 3****FIG. 4****FIG. 5****FIG. 6****FIG. 7****FIG. 8****FIG. 9****FIG. 10****FIG. 11****FIG. 12****FIG. 13****FIG. 14****FIG. 15**UNITED STATES PATENT AND TRADEMARK OFFICE
CERTIFICATE OF CORRECTION

PATENT NO. : Des. 326,351
DATED : May 26, 1992
INVENTOR(S) : Craig L. FELLER; and Charles JOHNSON

It is certified that error appears in the above-identified patent and that said Letters Patent is hereby corrected as shown below:

On the title page, Item [75] and Item Item [22]:

Line 2, delete "; John S. Earle, both" and
insert --,-- therefor;

Lines 5-6, delete "; David Collins,"
Taichung, Taiwan";

Line 11, delete "13" and substitute --31--
therefor.

Signed and Sealed this
Tenth Day of August, 1993

Attest:

MICHAEL K. KIRK
